Primary Examiner — Caron D Veynar*Assistant Examiner* — Martie K Holtje(74) *Attorney, Agent, or Firm* — Muncy, Geissler, Olds & Lowe, PLLC(57) **CLAIM**

The ornamental design for "air multiplier," as shown and described.

DESCRIPTION

FIG. 1 is a perspective view of "air multiplier" showing my new design thereof;

FIG. 2 is a right side elevational view, the left side being a mirror image thereof;

FIG. 3 is a top plan view thereof;

FIG. 4 is a front elevational view thereof;

FIG. 5 is a bottom plan view thereof;

FIG. 6 is a rear elevational view thereof; and,

FIG. 7 is a bottom perspective view taken from the side opposite that shown in FIG. 1.

The inner circles of the two sets of concentric circles in the FIG. 5 view, depicted by means of broken lines, form no part of the claimed design.
